UNITED STATES PATENT OFFICE.

ARTHUR M. ROLAND, OF SAN FRANCISCO, CALIFORNIA.

DISPENSING DEVICE.

1,159,275.

Specification of Letters Patent.

Patented Nov. 2, 1915.

Application filed June 1, 1914. Serial No. 842,286.

To all whom it may concern:

Be it known that I, ARTHUR M. ROLAND, a citizen of the United States, residing at San Francisco, in the county of San Francisco, State of California, have invented a new and useful Dispensing Device, of which the following is a specification in such full and clear terms as will enable those skilled in the art to construct and use the same.

10 This invention relates to a portable tank for gasoline or oil and its object is to produce a portable tank which will have a suitable apparatus connected therewith to discharge the gasoline or oil from the same in measured quantities without attention upon the part of the operator when once the apparatus has been started.

15 It will be understood by those skilled in the art that around garages and automobile supply stations, there is usually a plentiful supply of compressed air so that it is usually possible to operate any desired machinery in that way. In this instance a tank to be charged is connected to the gasoline tank and carried around therewith to operate the gasoline pump, said pump discharging gasoline so long as there is a supply of compressed air in the air tank.

20 Another object of the invention is to provide a device for automatically discharging a number of desired different amounts of the liquid. If it is desired to discharge the liquid a quart at a time, it may be done, or if a gallon at a time is desired, that amount 25 may be discharged.

25 In the drawings, in which the same reference numeral is applied to the same portions throughout, Figure 1 is a vertical elevation of the completed apparatus, a portion of the 30 tank being shown in vertical section for purposes of illustration. Fig. 2 is a plan view of the completed apparatus. Fig. 3 is a vertical sectional view of the completed apparatus on the line 3—3 of Fig. 1. Fig. 4 is a plan view of the pump cylinder. Fig. 5 is a view of the end of the pump cylinder showing its position with respect to the bottom of the gasoline tank. Fig. 6 is a vertical sectional view through the 35 engine cylinder. Fig. 7 is a front elevation of the engine cylinder and valve-box. Fig. 8 is a horizontal sectional view of the engine cylinder. Fig. 9 is a side elevation of the pump lever operating apparatus and Fig. 10 is a plan view of the pump lever link.

The numeral 1 is applied to the gasoline receptacle, which in this instance is a rectangular tank of any desired size, said tank being supported on wheels 2 and 3, which 40 with the trunnions 4 and 5 connected to the tank, form a carriage.

At the front end of the tank there is a suitable bracket 6, and caster-wheel 7, carried by a revolving standard 8, extending 45 into the bracket 6. On each end of the tank there is a bail, as indicated at 9 and 10, for the use of the operator in pulling the tank around from place to place. On the bottom of the tank there are two metal bands 70 11 and 12. Said bands support an air-tank 13 for the storage of the compressed air necessary to operate the apparatus. The air tank 13 is provided with a discharge pipe 14, having a suitable connection 15 for 75 supplying the tank with compressed air when the air contained therein has been discharged. The pipe 14 has a valve 16 for the regulation of the air when the gasoline is to be discharged from the apparatus, a 80 pipe 17 extending from said valve to the valve-box 18 on the side of the engine cylinder 19. At the side of the air cylinder below the tank there is a pump cylinder 20. This pump cylinder is closed by means of a 85 plug 21, at one end, and a plug 22 at the other end, the latter plug having a pipe 80 connected therewith for the discharge of the gasoline therethrough, and also having a chamber 24 therein which has an opening 90 in register, with an opening in the top of the pump cylinder 20. At the back of the chamber 24, there is an opening leading into the pump cylinder, which opening is covered by means of the valve 25, said valve being 95 suitably weighted to remain closed normally, although it is free to open upon the return stroke of the pump piston. In order to provide a definite stop for the pump piston 26, a flange 27 is formed within the 100 pump cylinder. At the end of the pump cylinder adjacent to plug 21, there is a long slot 28, said cylinder having suitable flanges 29 and 30 for connecting it to the bottom of the gasoline tank, a suitable gas- 105 ket 31 being interposed between said cylinder and the pump cylinder to prevent leakage. It will also be observed that there is a bolt 32 adjacent to the stop 27 for connecting the pump cylinder and tank bottom 110 in order to insure a tight joint with the opening 33 in the bottom of the tank.

The piston 26 has a link 34 connected therewith for operating same, which link is connected to a long lever 35, mounted upon the trunnion 36, bolted to the side of the casting at 37. At the upper end of the lever there is a short link 38 pivotally connected therewith. The link 38 has two brackets 39 and 40 bolted thereto, which brackets carry a rod 41, on which rod two spiral springs 42 and 43 are placed. These two spiral springs contact with a lever 44 and permit a certain movement thereof, necessary to the operation of the apparatus, as will be later explained. At the end of the link 38 there is a hook 45, which hook is connected with a spiral spring 46, said spring being connected at its opposite end to a ring 47 in the opposite end of the tank 1. The lever 44 is carried by a shaft 50, extending vertically through a bearing 51 bolted to the top of the gasoline tank. This shaft 50 carries on its upper end a similarly placed lever 52 to the lever 44, the former being connected with the piston rod 53, said piston rod being pivotally supported at its opposite end in lugs formed on piston 54, said piston being movable in the cylinder 19. At the side of the back end of the cylinder 19 there is a valve-box 18, within which there is installed an oscillating valve 55. This valve has ports 56, 57 and 58 and is so positioned that when the valve operating rod 59 is reciprocated, that it will be operated by means of the short arm 60, connected therewith, to shift it from the inlet position as indicated in Fig. 8, to such a position as will permit the port 58 to register with the exhaust port 62 in the valve-casing 18. The valve operating rod 59 is carried in slides 63 and 64 on the side of the cylinder 18 and it has an extension 65 which is provided with an upward extending arm 66 for the operation thereof. The piston rod 53 is provided with a depending bracket 67, which upon the return stroke of the pump contacts with the arm 66 and returns the valve in the casing 18 to the inlet position, while to measure any particular quantity of gasoline, the stop arm 68 pivotally connected with the piston at 69, is moved from one position to another so that either of the stops 70—71 or 72 may contact with the arm 66, and since the arms 65 and 66 are made strong enough to stop the apparatus even when under pressure, they will not only cause the reversal of movement of the piston by the releasing of the air in the cylinder 19, but will act as means for absolutely determining the precise quantity of fluid to be discharged from the pump. The rod 59 is provided with a stop 73 in order to precisely determine the point at which the piston will be finally stopped. In order to adjust the arm 68, a spring 74 bears upon the same and tends to hold it down, while it is provided with an upwardly extending

arm 75 and with a lateral extension 76, which lateral extension is provided with a plurality of notches 77, as indicated in Fig. 7, thus enabling the operator to shift the stop as he may desire to discharge more or less gasoline at each stroke.

In order to fill the tank a cap 76 in the top thereof is provided. The operation of the apparatus is as follows, it being assumed that the tank is filled or partially filled with gasoline: The air tank is charged with air at a suitable pressure. The normal position of the apparatus is indicated in Fig. 3, in which the spring 46 has caused the pump piston to fill the pump cylinder with gasoline. After being so filled with gasoline the operator opens the valve 16, whereupon air will pass into the engine cylinder (note Fig. 8) and will force the piston therein outwardly, until one of the stops or the piston itself contacts with the valve operating rod, whereupon the valve will be turned to the exhaust position and the gasoline will have been delivered through the discharge pipe 80, connected with the pump, whereupon the pump piston will be returned to the position shown in Fig. 3, by the spring 46, said spring being only heavy enough to insure the return of the apparatus to the initial position ready for another discharge. It will be apparent that so long as valve 16 remains open that gasoline will be discharged from the apparatus in definite volumes intermittently, the valve 25 allowing the gasoline to run from the tank into the pump cylinder and preventing its return to the tank. The pipe 80 is provided with a hose connection 81' and faucet 82, such as is commonly used in the art. The object of the springs 42—43 is to allow a slight movement of the position of the pump pistons and engine pistons with respect to each other, to insure against injury to one part or the other.

In order to enable the purchaser to know that he is getting the amount of gasoline he has asked for a suitable registering or indicating meter M is installed in the pipe 80 at the top of the tank.

It is to be especially noted that the gasoline tank is practically air tight, save for the opening necessary to permit the removal of the gasoline therefrom, and that the air used for the operation of the pump cannot at any time get into the gasoline tank.

Having thus described my invention what I claim as new and desire to secure by Letters Patent of the United States, is as follows, modifications within the scope of the claims being expressly reserved.

1. A liquid receptacle comprising a tank, a pump connected therewith and supported by the tank below the same, an air tank, a pressure cylinder, a piston therein, pipe connections between the pressure cylinder and air tank to operate the piston, a lever within the

tank, and connections between the lever, the pressure cylinder and pump to operate the latter.

2. A liquid receptacle comprising a tank, a pump cylinder carried by the tank below the same and having an opening into the bottom of the tank, an air tank, a pressure cylinder, a piston in said cylinder, connections to supply said cylinder with air from the air tank, 5 a lever within the tank connected with the pump piston, and connections between the lever and pressure cylinder piston whereby the pump will be operated on the admission of air under pressure to said cylinder.
- 10 3. The combination of a tank, a pump supported by the tank below the same and receiving liquid therefrom, an engine above the tank, an air pressure cylinder, means connected with said air pressure cylinder and 15 said engine for the operation of the engine, and connections extending between said engine and pump whereby the pump may be operated.
4. The combination of a tank, a pump cylinder below the same and receiving liquid therefrom, an engine cylinder above the tank, an air cylinder, connections between the air cylinder and engine for the operation thereof, a valve to permit the air to pass under 20 pressure to the engine cylinder, connections between said engine and pump for the operation thereof, and means to restore the pump

piston to its initial position after a quantity of liquid has been expelled therefrom.

5. The combination of a tank, a pump below the same and receiving liquid therefrom, means extending through the tank for the operation of the pump, an engine cylinder, an air pressure cylinder, connections between 35 said air pressure cylinder and the engine cylinder to admit air to the engine cylinder, and an adjustable stop for varying the stroke of the engine cylinder.

6. The combination of a tank, wheels secured thereto for the support of the same, 40 an air pressure cylinder and a pump cylinder supported by the tank below the same, means extending through the tank for the operation of the pump, an engine cylinder above the tank, connections between the air 45 cylinder and engine cylinder for the supply of compressed air to the engine cylinder, and an adjustable stop carried by the engine piston connecting rod for causing the discharge of different volumes of liquid from said 50 pump.

In testimony whereof I have hereunto set my hand this 25th day of May A. D. 1914, in the presence of the two subscribed witnesses.

ARTHUR M. ROLAND.
